CLAIM

The ornamental design for a beach mesh shovel, as shown and described.

DESCRIPTION

FIG. 1 is a front perspective view of a beach mesh shovel, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is a perspective view showing the beach mesh shovel in a use state thereof;

FIG. 10 is a perspective view showing the beach mesh shovel in a split state thereof; and,

FIG. 11 is an enlarged detail view of area 11 in FIG. 2.

The broken lines in the drawings illustrate the portions of the beach mesh shovel, which form no part of the claimed design.

The dash-dot-dash broken lines encircling the enlarged views are for annotative purposes only and form no part of the claim thereof.
